MUFFLE FURNACE

Harold N. Ipsen, Rockford, Ill.

Application June 18, 1951, Serial No. 232,158

6 Claims. (Cl. 263—42)

1

The present invention relates to fired heat treating furnaces of the type in which articles to be treated are heated in a hollow muffle disposed within the furnace.

One object of the invention is to bring about a more uniform heating of the furnace muffle through improvements in the distribution of heating gases around the muffle effected by a division of the streams of burning gases entering the furnace from the burners and a redirection of a portion of the gases toward certain areas of the muffle which have heretofore been improperly heated.

In connection with the foregoing, another object is to eliminate hot spots on the muffle and thereby avoid one of the major factors which has heretofore produced overheating of contiguous interior portions of the muffle and tended to cause deterioration of the muffle.

Other and related objects are to produce a more uniform heating effect on objects within the muffle and to increase the operating efficiency of the furnace.

A particular object is to provide a conversion unit which can be conveniently incorporated into furnaces already in use so as to improve their operation in accordance with the invention.

The objects of the invention thus generally set forth, together with other objects and ancillary advantages are attained by the construction and arrangement shown by way of illustration in the accompanying drawings, in which:

Figure 1 is a vertical sectional view taken along the line 1—1 of Fig. 2 and showing a muffle furnace embodying the present invention.

Fig. 2 is a vertical sectional view taken along line 2—2 of Fig. 1.

Fig. 3 is a perspective view showing a gas distributing block constructed in accordance with the invention.

Fig. 4 is an exploded, fragmentary perspective view showing a gas distributing block and a section of the furnace wall having a burner opening and gas distributing recess therein and indicating the relationship of these parts when in assembled position.

Fig. 5 is a fragmentary sectional view taken generally along line 5—5 of Fig. 1.

Fig. 6 is a schematic view showing the relationship to each other of the gas distributing blocks as assembled in the furnace.

The present invention is applicable to fuel burning muffle furnaces of various specific designs and constructions. Hence, it will be understood that there is no intention to limit the in-

2

vention to its application to furnaces of the exact design shown in the drawings and described herein. On the contrary, it is intended to cover all embodiments and alternative constructions of the invention falling within the spirit and scope of the invention as expressed in the appended claims.

Referring more particularly to the drawings, the muffle furnace 10, selected for the purpose of illustrating the instant embodiment of the invention, comprises a shell 11 defining a large internal chamber 12. As shown, this shell is formed from thick heat insulating panels including a floor 14, spaced side walls 15, and a ceiling 16. A hollow muffle 17 formed from adjoining bottom, side, and top panels 19—21, is supported in the chamber 12 in spaced relation to the contiguous furnace panels. The muffle panels with the opposed furnace panels define gas passageways 22 extending under the muffle and passageways 24 extending upwardly and around the muffle. Heating of the muffle 17 is effected by burners 25 mounted in openings 26 extending through the opposed furnace side walls 15 in general alignment with the passageways 22 under the muffle 17.

The furnace thus formed is of a conventional design generally used in the heat treating art. Experience in the operation of such furnaces has revealed that the heating effect of the furnace gases on the muffle 17 has heretofore been concentrated on limited areas of the muffle panels. Accordingly, these areas have been overheated while other portions of the muffle have not been adequately heated. In particular, the bottom panel 19 of the muffle has been overheated by the burning gases sweeping under the muffle 17 while the side panels 20 have been poorly heated by an uneven flow of cooled gases passing up through the passageways 24.

This unevenness in the heating of the muffle has not only tended to cause deterioration of the muffle but has brought about a non-uniform heating of the objects heat treated in the furnace. It will be understood that non-uniformities in the temperature to which the objects are raised produces consequent variations in the physical characteristics imparted to the objects by the heat treating process.

In accordance with the present invention a more uniform heating of the muffle 17 is brought about by dividing the streams of burning gases entering the furnace chamber 12 from the burners 25 and diverting portions of the gases upwardly through the contiguous passageways 24

while directing the remaining portions of the gases through the passageways 22 under the muffle.

Implementation of the invention is effected by placing in front of the respective burners 25 gas dividers or baffles 27 which are especially constructed to divide the streams of burning gases and bring about an effective heating of the side panels 20 while at the same time avoiding overheating of the bottom panel 19. A deflecting surface 29 is formed on each baffle 27 to extend upwardly from an intermediate level relative to the stream of gases which issues from the adjacent burner 25 and is effective to divert upwardly the top portion of this gas stream to heat the contiguous muffle side panel 20. In the illustrated embodiment of the invention the lower extremities of the deflecting surfaces 29 are on a level with the extended axes of the burner openings 26 in the furnace walls, but it will be understood that the relative height of these extremities can be varied in different furnaces to bring about the most efficient division of gases between the horizontal gas passageways 22 and the vertical passageways 24.

In the preferred construction illustrated, each baffle 27 comprises an upright elongated block of refractory material, the lower end of which comprises an enlarged base 30 adapted to rest on the furnace floor 14 and project a short distance into the inner end of the adjacent one of the burner openings 26, Figs. 1 and 5. The outer side face of each baffle block 27 is curved inwardly from the top of the base 30 to form the deflecting surface 29 of the baffle. As shown, this surface is curved rather sharply at its lower end but straightens out toward its upper end.

The central portion of the base 30 of each baffle block 27 is formed with a downwardly open rectangular recess 31 facing the furnace floor 14 and extending from the front to the back side of the block. The recess thus provided defines a transverse channel through which burning gases are directed into the passageway 22 extending under the burner. Preferably, the channel recess 31 of each baffle block extends upwardly to the lower end of the deflecting surface 29, the roof of the channel intersecting the surface to define a clear cut gas dividing edge 32, Figs. 3 and 5.

As shown, the channel recess 31 of each baffle base 30 is substantially equal in width to the diameter of the adjacent one of the orifices 34 of the burners 25, Figs. 2 and 5. Structural material of each base on opposite sides of the base recess 31 forms two opposed depending support legs 35 which rest on the furnace floor 14. It will be observed that the streams of burning gases which flow from the channels 31 through the horizontal passageways 22 are sufficiently removed from the bottom muffle panel 19 to prevent the formation of hot spots on the panel, while at the same time effectively heating the panel to operating temperatures.

In instances, such as the present one, in which the furnace burners 25 are employed on opposite sides of the furnace 10, the opposed burners are normally located in staggered relation to each other. This relationship of the burners is shown in Figs. 1 and 2, but it can be better visualized with reference to Fig. 6 which shows the relative location of the baffle blocks 27 as disposed in front of the respective burners.

Taking cognizance of this staggered burner arrangement, further provision is made in accord-

ance with the invention for effecting a greater lateral dispersion of the burning gases diverted upwardly by the baffles 27. For this purpose the deflecting surfaces 29 of the baffles are given a small lateral "twist" or curvature which acts to spread the hot gases entering the vertical passageways 24 laterally over the muffle side panels 20. Preferably, the direction of twist of each deflecting surface 29 is such that the gases passing over the surface are directed to the side of the associated burner 25 lying across from the opposed burner on the opposite side of the furnace.

In instances in which the baffles 27 are incorporated into furnaces at the time they are built, the side walls of the furnace are preferably formed with recesses 36 which extend upwardly and laterally from the inner end of each burner opening 26 for cooperation with the baffles in expediting the direct distribution of burning gases into the vertical passageways 24. As shown in Figs. 1, 2, 4, and 5, the recesses 36 are generally fan-shaped and progressively decrease in lateral depth longitudinally of the burners 25 from the lower ends of the recesses which intersect the burner openings 26 to the upper extremities of the recesses which extend somewhat above the baffles 27. It will be noted that the recesses 36 gradually increase in width to extend laterally to one side of the burner openings 26 to conform in shape to the flow lines of the gases diverted upwardly and laterally by the respective baffles 27.

It will be understood that the invention is susceptible of being used with furnaces already in operation as well as in new furnaces. The baffle blocks 27 provided by the invention form conversion units which may be incorporated into conventional furnaces of the type described without any substantial modification of the furnaces.

As shown in Figs. 1 and 5, the burners 25 of conventional furnaces are commonly provided with rather large burner blocks 37 which fit directly into the burner openings 26. To permit the installation of the baffle blocks 27 into a furnace, the burner blocks 37 are removed from the burner openings which usually are formed to have a rectangular or square transverse shaping. The baffle blocks 27 are then inserted longitudinally through the burner openings 26 and erected in front of the burner openings, as shown in the drawings. The burners including the blocks 37 are replaced and the furnace is again readied for operation with the baffles 27 assembled in working positions.

If desired the recesses 36 can be dug into the furnace walls 15 by working through the burner openings 26. However, significant improvements in the operating characteristics of the furnace are realized when the distribution blocks are used without the cooperating recesses 36.

It will be evident that the elimination of hot spots on the furnace muffles prolongs the life of the muffles. At the same time, it achieves a more even distribution of heat to the muffle with the result that the physical properties imparted to objects heat treated in furnaces equipped with the invention are improved and made more uniform. Moreover, the uniform distribution of heat makes practical the use of a silicon carbide structural material in the fabrication of the muffles, it being understood by those in the art that the properties of silicon carbide as used in these muffles have certain advantages in themselves provided the material is protected from excessive and spotty heating as it is by the invention.

Other worthwhile accomplishments attributable to the invention include increases in the heating and operating efficiency of muffle furnaces which stem from the improved distribution of burning gases about the furnace muffles.

I claim as my invention:

1. A muffle type heat treating furnace comprising, in combination, a plurality of adjoined furnace walls including a floor wall and an adjoined side wall defining an internal chamber, a hollow muffle disposed in said chamber in spaced relation to certain ones of said furnace walls including said floor wall and said side wall so as to define a first gas passageway under said muffle and a second gas passageway between said muffle and said side wall, a fuel burner in said side wall and substantially alined with said first passageway, a combustion gas distributing member disposed between said burner and the contiguous portion of said muffle and comprising an upright elongated block having an enlarged base and a vertically elongated upper portion, said base including spaced downwardly extending support legs resting upon said floor wall and cooperating with the body of said block to define a transverse channel extending through said base from the front to the back side thereof for permitting one portion of the combustion gases issuing from said burner to flow through said block into said first passageway, and said elongated upper portion of said block having an inwardly and upwardly curved deflecting surface facing said burner and extending upwardly from the vicinity of the upper portion of said channel to divert directly into said second passageway a second portion of the gases from said contiguous burner.

2. A muffle type heat treating furnace comprising, in combination, a plurality of adjoined furnace walls including a floor wall and opposed side walls defining an internal chamber, a hollow muffle disposed in said chamber in spaced relation to certain ones of said furnace walls including said floor wall and said side walls so as to define combustion gas passageways under and around said muffle, a plurality of burner openings extending through said opposed side walls in staggered relation to each other and having burners therein substantially alined with the passageway under said muffle, a plurality of combustion gas distributing members equal in number to said burners and individually disposed between said respective burners and contiguous portions of said muffle, each of said members comprising an upright elongated block having an enlarged base extending a short distance into the inner end of the contiguous burner opening and including spaced downwardly extending support legs resting upon said floor wall and cooperating with the body of said block to define a transverse channel extending through said base from the front to the back side thereof, and extending upwardly to the level of the extended axis of the contiguous burner thus permitting one portion of the combustion gases which issue from said contiguous burner to flow through said block into said passageway under said muffle, each of said blocks having an elongated upper portion extending vertically above the base of the block and defining an inwardly and upwardly curved deflecting surface facing the contiguous burner and diverting directly into the contiguous one of said passageways between said side walls and said muffle a second portion of the gases which issue from said contiguous

burner, said deflecting surfaces on said respective blocks being slightly twisted laterally so as to disperse said second portions of gases laterally in wide streams in opposed relation to staggered burners in the opposite furnace side wall.

3. A muffle furnace comprising, in combination, a plurality of furnace walls defining an internal chamber, a hollow muffle disposed within said chamber in spaced relation to certain ones of said furnace walls so as to define therewith combustion gas passageways extending under and around said muffle, one of said walls defining a burner opening located in contiguous relation to the lower portion of said muffle, the inner face of said one wall defining a recess therein extending upwardly from the inner end of said burner opening, said recess gradually decreasing in its lateral depth and gradually increasing in its lateral width from its lower to its upper end, an upright baffle supported in said furnace between the inner end of said burner opening and said muffle, means on said baffle defining a gas deflecting surface extending upwardly from the vicinity of the extended axis of said burner opening, said deflecting surface being disposed in spaced relation to the opposed bottom surface of said recess and serving to deflect a certain portion of the gases entering through said burner opening upwardly between said muffle and the contiguous one of said furnace walls and at the same time permitting the remaining portion of the gases to flow under the muffle between the muffle and the lower one of said furnace walls.

4. A muffle type heat treating furnace comprising, in combination, a plurality of adjoined furnace walls defining an internal chamber, a hollow muffle disposed in said chamber in spaced relation to certain ones of said furnace walls to define therewith combustion gas passageways under and around said muffle, a plurality of fuel burners disposed on one of said walls in general alinement with said passageway under said muffle, a plurality of combustion gas distributing members equal in number to said burners and individually disposed between said respective burners and contiguous portions of said muffle, each of said members comprising a block of refractory material having a transverse channel defined in the lower end thereof and extending through said block from the front to the back side thereof for permitting one portion of the combustion gases issuing from the contiguous burner to flow through said block into said passageway under said muffle, the upper portion of each of said blocks having an upwardly extending deflecting surface thereon facing the respective burners and extending upwardly to divert directly into said passageway between said one furnace side wall and said muffle a second portion of the gases from the contiguous burner, and said deflecting surface on each of said blocks being slightly twisted laterally so as to disperse said second portions of gases laterally in wide streams.

5. A muffle type heat treating furnace comprising, in combination, a plurality of adjoined furnace walls defining an internal chamber, a hollow muffle disposed in said chamber in spaced relation to certain ones of said furnace walls to define therewith combustion gas passageways under and around said muffle, a plurality of fuel burners disposed in at least one of said walls in general alinement with said passageway under said muffle, a plurality of baffles equal in number

to said burners and disposed between said respective burners and said muffle, each of said baffles defining a deflecting surface having one edge in the stream of gases issuing from the adjacent one of said burners and extending upwardly from said edge with a twisted curvature to direct one portion of the gas stream upwardly and laterally into the passageway between said one wall and said muffle while permitting another portion of the stream to flow under said edge and through the passageway under said muffle.

6. A combustion gas distributing member for use in a muffle type heat treating furnace, said member comprising a block of refractory material adapted to be disposed in alignment with a furnace burner, and means on the lower portion of said block defining an elongated channel extending from the front to the back side of the

5 block to permit the passage of a portion of the combustion gases therethrough, the front side of said block defining a deflecting surface extending upwardly above said channel and twisted laterally to deflect another portion of the gases upwardly and laterally relative to the block.

HAROLD N. IPSEN.
